(57) **CLAIM**

The ornamental design for a notebook computer with slideable and rotatable display, as shown and described.

DESCRIPTION

FIG. 1 is a perspective view of a notebook computer with slideable and rotatable display showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view of the notebook computer shown in an alternate configuration with the display slid upward;

FIG. 10 is another perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof;

FIG. 16 is a bottom view thereof;

FIG. 17 is a perspective view of the notebook computer shown in another alternate configuration with the display slid upward;

FIG. 18 is another perspective view thereof;

FIG. 19 is a front view thereof;

FIG. 20 is a rear view thereof;

FIG. 21 is a left side view thereof;

FIG. 22 is a right side view thereof;

FIG. 23 is a top view thereof;

FIG. 24 is a bottom view thereof;

FIG. 25 is a perspective view of the notebook computer shown in another alternate configuration with the display rotated 90°;

FIG. 26 is another perspective view thereof;

FIG. 27 is a front view thereof;

(Continued)

FIG. 28 is a rear view thereof;
 FIG. 29 is a left side view thereof;
 FIG. 30 is a right side view thereof;
 FIG. 31 is a top view thereof; and,
 FIG. 32 is a bottom view thereof.

The evenly-dashed broken lines depict portions of the notebook computer with slidable and rotatable display that form no part of the claimed design. The dot-dash broken lines define the bounds of the claimed design and form no part thereof.

1 Claim, 32 Drawing Sheets
